YARN TWISTING APPARATUS

William Pool, Spondon, near Derby, England,
assignor to Celanese Corporation of America,
a corporation of Delaware

Application August 3, 1934, Serial No. 738,188
In Great Britain August 18, 1933

5 Claims. (Cl. 117—23)

This invention relates to improvements in yarn twisting apparatus, and is an improvement in or modification of the yarn twisting device described in U. S. Patent No. 1,949,621.

5 The twisting device according to the prior specification is of the "double twist" type, and comprises a pair of interconnected friction rollers adapted to be carried round by a member rotat-
10 ing the twisting spindle and to contact respective-
ly with an annular race connected to the yarn package and an annular race independent of the package. The arrangement affords a simple and effective means for "gearing" the yarn pack-
15 age to a member independent of the means by
which twist-applying rotation is imparted to the device, notwithstanding the package having to be supported within the balloon of yarn which rotates completely round the package for the purpose of imparting the "double twist". In the
20 prior specification the friction rollers are de-
scribed as being loosely mounted on their pivot so that they are pressed outwardly by centrifugal force and caused to bear firmly against the two annular races.

25 In one of its aspects the present invention con-
sists in an improved mounting for the friction rollers in order to take full advantage of centrifugal force in obtaining firm driving contact.

According to the invention the friction rollers
30 are recessed at the two ends of their axes to re-
ceive a pair of balls which engage grooves in the member by which the rollers are carried bodily round the axis of the device, the grooves permitting the balls and therefore the rollers to move
35 outwards under centrifugal force. Most conven-
iently radial grooves are employed which confine the balls in a circumferential direction, but per-
mit them to move radially. The arrangement
40 provides a ball-bearing mounting for the friction rollers, thus permitting them to be accurately positioned while very freely rotatable, and at the same time provides for the free outward move-
45 ment of the rollers under the centrifugal force set up by the rotation of the member carrying the rollers.

A further important feature of the invention is that the friction rollers are of quite small diameter with consequent reduction in the internal diameter of the annular races, thus permitting
50 greater compactness of the apparatus and the possibility of higher speeds of operation. The friction rollers, in fact, may actually take the form of a single cylindrical roller having a diameter not greatly differing from that of the balls
55 by which it is supported in position. The roller

may be made of metal and so capable of being very accurately dimensioned, and, annular races engaging with such roller being also of accurate dimensions, the holding of the package substantially stationary within the balloon can be readily accomplished. Moreover, the friction rollers may be hardened so that very little wear occurs in operation, with consequent accurate working of the device over long periods. 5

Any desired number of friction rollers may be 10 employed, but in general two rollers arranged at diametrically opposed points are sufficient to transmit a firm, substantially vibrationless drive.

By way of example, one form of apparatus according to the invention will now be described 15 in detail with reference to the accompanying drawing in which:—

Fig. 1 is a part sectional elevation of the apparatus on the line 1—1 of Fig. 2.

Fig. 2 is a plan view in section along the line 20 2—2 of Fig. 1, partly broken away at the level 2'.

Fig. 3 is a sectional view of part of the apparatus shown in Fig. 1; and

Fig. 4 is a part sectional side elevation of Fig. 1. 25

A yarn package 5 is mounted on a platform 6 carried by a cylindrical member 7. The member 7 surrounds a hollow spindle 8, ball-bearings 9, 10 being provided between the member 7 and the spindle 8. The spindle 8 is rotated by means of 30 a wharl 11 carried by a bolster rail 12 and is provided with a disc-like member 13 round which is mounted a shield 14 extending upwardly and surrounding the base of bobbin 5. The spindle 8 is hollow and a horizontal passage 15 leads 35 outwardly from its interior through the member 13.

A ring 16 mounted on the bolster rail 12 carries an upstanding race 17 and a similar depending race 18 of precisely the same diameter is carried 40 by the cylindrical member 7. The two races 17, 18 are engaged by a friction roller 19 mounted in a recess 20 (Fig. 2) in the member 13. Recesses 21 in the top and bottom of the roller 19 carry ball-bearings 22 which engage in radial 45 V-shaped grooves 23 in the top and bottom of the recess 20 in the member 13. The ball bearings and the radial grooves are shown in Figs. 3 and 4. Two rollers 19 are provided and are disposed diametrically opposite in the member 13, 50 being engaged by appropriately disposed balls 22 as shown in Fig. 3.

When the spindle 8 is rotated by means of the wharl 11, the friction rollers 19 fly outwardly and are pressed by centrifugal force against the two 55

races 17, 18. In consequence, the two races are effectively geared together by the frictional engagement of the rollers 19, and although the rollers 19 rotate bodily with the spindle 8, the race 5 18 is caused to remain stationary with the fixed race 17. In consequence, the cylindrical member 1, platform 6 and bobbin 5 are kept stationary.

The yarn 25 drawn from the bobbin 5 is conducted over a brass cap 26 on the top of the 10 bobbin 5 through a guide eye 27 mounted on the end of a spiral spring 28, then outwardly over the edge of a disc 29. The yarn 25 then passes down a tube 30, which is plugged into the top of the bobbin 5 and carries the disc 29 and the 15 spiral spring 28. The tube 30 extends to the bottom of the bobbin 5 where it meets a tube 31 screwed inside the spindle 8. The yarn passes down tubes 30 and 31 and out through the passage 15 from which it proceeds in the form of a balloon 20 32 to a guide eye 33 on the axis of the device. The rotation of the spindle 8 and of the member 13 containing the passage 15 causes the balloon 32 to rotate round the stationary package 5 on which the yarn is drawn and, in consequence 25 two turns of twist are imparted to the yarn for each revolution of the spindle 8.

By reason of this frictionless mounting on the 30 balls 22 in the radial grooves 23, the friction rollers 19 may be permitted to rotate at a very high speed, and in consequence may be made of small diameter. This enables the diameter of the device in the neighbourhood of the friction rollers 19 to be reduced within the limits of the diameter of the bobbin 5 and its protecting shield 14. The 35 races 17, 18 being accurately ground to the same internal diameter and the rollers 19 being truly cylindrical, a firm connection is maintained between the races so as to keep the race 18 stationary. In order to reduce the weight of the device, 40 the several parts shown in the drawing may be made as die castings of light alloy adapted to be secured to one another.

What I claim and desire to secure by Letters Patent is:—

45 1. In a device adapted to impart to yarn drawn from a stationary yarn package two turns of twist for each revolution of the device, a member adapted to carry a yarn package, an annular race attached to said member, a fixed annular race, a rotatable member provided with grooves, a friction roller having a recess at each end, a pair of balls engaging said recesses and said grooves so that said roller is caused to rotate bodily with said rotatable member, said grooves being such as to allow the roller to fly outwards under centrifugal force and to engage with said annular races so as to keep said yarn package stationary.

50 2. In a device adapted to impart to yarn drawn

from a stationary yarn package two turns of twist for each revolution of the device, a member adapted to carry a yarn package, an annular race attached to said member, a fixed annular race, a rotatable member provided with grooves, 5 a friction roller in the form of a cylinder of small diameter having a recess at each end, a pair of balls engaging said recesses and said grooves so that said roller is caused to rotate bodily with said rotatable member, said grooves being such as to allow said roller to fly outwards under centrifugal force and to engage with said annular races so as to keep said yarn package stationary.

3. In a device adapted to impart to yarn drawn from a stationary yarn package two turns of 15 twist for each revolution of the device, a member adapted to carry a yarn package, an annular race attached to said member, a fixed annular race, a hardened metal friction roller in the form of a 20 cylinder of small diameter having a recess at each end, a pair of balls engaging said recesses and said grooves so that said roller is caused to rotate bodily with said rotatable member, said grooves being such as to allow said roller to fly outwards 25 under centrifugal force and to engage with said annular races so as to keep said yarn package stationary.

4. In a device adapted to impart to yarn drawn from a stationary yarn package two turns of twist 30 for each revolution of the device, a member adapted to carry a yarn package, an annular race attached to said member, a fixed annular race, a rotatable member provided with grooves, a pair of friction rollers, each having a recess at each 35 end, a pair of balls in connection with each roller engaging said recesses and said grooves so that said roller is caused to rotate bodily with said rotatable member, said grooves being such as to allow said roller to fly outwards under centrifugal 40 force and to engage with said annular races so as to keep said yarn package stationary.

5. In a device adapted to impart to yarn drawn from a stationary yarn package two turns of twist for each revolution of the device, a member 45 adapted to carry a yarn package, an annular race attached to said member, a fixed annular race, a rotatable member having at least one cylindrical recess provided with grooves, at least one friction roller having a recess at each end and adapted to be accommodated in said recess, a pair of balls in connection with such roller engaging said recesses and said grooves so that said roller is caused to rotate bodily with said rotatable member, said grooves being such as to allow said roller 50 to fly outwards under centrifugal force and to engage with said annular races so as to keep said yarn package stationary.

WILLIAM POOL.
